UNITED STATES PATENT OFFICE

1,988,887

WORK HOLDER

Orlan G. Armstrong, Canton, Ohio

Application March 14, 1934, Serial No. 715,544

9 Claims. (Cl. 51—217)

The present invention relates to work holders and more particularly to a tool or device for use in grinding or re-surfacing contact points of ignition systems, such as are employed in connection with internal combustion engines.

The primary object of the invention is to provide a device of this character adapted to receive and hold various types of movable contact arms or levers, as well as different forms of contact

10 screws, so that the contact points thereof may be properly ground or re-surfaced.

A further object of the invention is to provide a work holder for use in connection with ignition point grinding and adapted to be associated with 15 existing types of valve grinding or re-surfacing machines having means for squaring off the ends of the valve stems.

Another and important object of the invention is to provide a work holder of this character 20 which may be very economically manufactured and sold at a low cost so that the holder may be profitably used as equipment in garages and repair shops generally.

Still another object is to provide such a device 25 which is not apt to become clogged by the material ground off nor one which will easily get out of order.

Other objects and advantages of the invention will be apparent during the course of the following detailed description, taken in connection with the accompanying drawing forming a part of this 30 specification and in which drawing:

Figure 1 is a top plan view of a conventional valve grinding machine with the novel work 35 holder in position upon the machine and a double contact arm gripped by the holder.

Figure 2 is an elevation of the novel work holder.

Figure 3 is a view substantially on the line 40 3—3 of Figure 1.

Figure 4 is a fragmentary longitudinal sectional view thru one end of the holder and showing one type of contact screw held in position for grinding.

45 Figure 5 is a fragmentary elevation of an end of the holder showing the manner of placing a second type of contact screw in the holder.

Figure 6 is a fragmentary sectional view showing the second type of contact screw held in position for grinding.

Figure 7 is an enlarged end view of the holder showing another type of contact arm held in position for grinding.

50 Figure 8 is a longitudinal section thru the holder showing the normal relation of the parts.

In the drawing, wherein for the purpose of illustration is shown only a preferred embodiment of the invention, the letter A designates generally a conventional form of bench tool or valve grinding machine, the letter B the novel work holder, C one type of contact point, D a screw type contact point, E a second screw type contact point, and F a fourth type of contact point.

For the purpose of illustration, the valve grinding machine A is one shown and described in U. S. Patent 1,803,984, dated May 5, 1931. This machine includes a grinding tool, such as an abrasive wheel 10, suitably mounted to rotate, a work spindle base 11, provided with an elongated substantially V-shaped guide depression or groove 12 in its upper surface, the groove normally extending towards the face of the abrasive wheel 10 with the ends of the groove open. Means is provided in the patent referred to, so that the extended plane of the groove 12 will intersect and substantially form a right angle with the face of the wheel 10.

As for the novel work holder B, the same includes an elongated housing which preferably comprises a tubular member 15. One end 16 of the tubular member may be somewhat flattened so as to provide a mouth 17 narrower in width than the internal diameter of the tubular member but wider in length than the internal diameter thereof as is particularly shown in Figure 7. The extremity of this end 16 forms an abutment 18 of some length. Extending longitudinally of the tubular member is a slot or opening 19 which extends from the outer to the inner surface of the tubular member and to either side of the transverse medial line thereof and ends well short of the ends of the tubular member. Adjacent the end 20 opposite the end 16 the tubular member is provided with an opening 21 having a substantially rectangular mouth and communicating with the interior of the tubular member. This opening 21 is spaced from the extremity of the end 20 and between it and the said extremity the tubular member is provided with a perforation 22 which may be screw threaded if desired. Inwardly of the mouth 17 and on opposite sides of the tubular member, the latter may be provided with a pair of rivet holes for a purpose later brought out.

Slidably within the housing or tubular member 10 is a preferably short plunger 23 having generally squared ends, the extremity of the end facing the mouth 17 being provided with a groove or recess 24 while the extremity of the opposite end of the plunger 23 provides an abutment 55

Suitably fixedly secured to the plunger 23 may be a means to slide the plunger thru the tubular member and which preferably comprises a pin 26 extending thru the slot 19 and terminating in a head 27 such as shown in Figures 3 and 8.

Work holding means at one end of the tubular member comprises an insert or member 28. This member 28 is snugly held within the tubular member against movement so that it closes the end 20 of the tubular member. However, it is provided with a longitudinal bore 29 of a circumference so that an abutment 30 is provided at the inner end of the member 28. A transverse bore 31 extends thru the member to the longitudinal bore 29 and is preferably screw threaded. This bore 31 when aligning with the perforation 22 permits the insertion of a screw 32 having the function of holding the insert 27 in place as well as an additional function later described.

A second work holding means, differing radically from the last described means, is provided at the end 16 and preferably includes a substantially U-shaped member with the bight portion 33 thereof accommodated within the recess 24 of the plunger 23. The arms 34 of the U-shaped member extend along the inner surfaces of the side walls of the tubular member and are preferably of resilient material. The width of the arms is such that, as may be seen in Figure 2, they bridge the slot 19. Since the arms may be said to extend from the plunger 23, the slot 19 is always covered no matter what may be the position of the plunger 23 nor the arms 34, whereby no abrasive material nor metallic particles ground off will find their way to the interior of the housing thru this slot. The arms 34 normally extend to a short distance inwardly of the abutment 18 and lie within the mouth 17 and across the narrow end thereof, being normally spaced somewhat from the walls of the mouth as shown in Figure 7. The free ends of the arms terminate in fingers 35 which extend inwardly towards the longitudinal axis of the tubular member and in substantial parallelism with the abutment 18. It will be seen in Figures 3 and 7 that these fingers 35 terminate short of each other.

A single resilient means is provided both to normally urge the plunger 23 toward the member 28 in the end 20 of the tubular member so as to force the plunger against the work held by the first described work holding means and to also normally urge the second work holding means toward the end 20 of the tubular member. It is preferred to employ an extension coil spring 36 for this purpose, the coil spring having its innermost end 37 terminating in an eye thru which a suitable pin 38 extends so as to couple the spring 36 to the plunger 23. This pin 38 bridges the recess 24 inwardly of and adjacent the end of the plunger and lies between the end and the bight portion 33 of the U-shaped member, thus both securing the coil spring 36 to the plunger 23 and also holding the U-shaped member coupled thereto. The opposite end 39 of the spring 36 is secured by a suitable rivet or pin 40 extending thru the rivet holes mentioned as adjacent the mouth 17.

The contact points C to F inclusive are examples of types which may be held by the novel work holder B. C is a double contact arm form, wherein in a block 50 of dielectric material having an arm portion 51 substantially rectangular in transverse cross section, carries a conductor 52 and a contact pin 53 extending above the surface of the arm 51 and conductor 52. In the contact screw

D, a head 55 and screw threaded shank 56 of substantially similar diameter are provided, the shank terminating in a contact point 57, while in the contact screw E a head 60 is provided together with a shank 61 of less diameter, and the latter terminates in a contact point 62. A fourth type of contact point is shown in Figure 7 as F. This includes an arm 65 having a contact point 66 projecting therefrom.

When employing the novel tool holder B in grinding the contact points 53 of the contact arm C, the tool holder B may be grasped in one hand and the thumb or a finger employed to urge the head 27 towards the end 16 until the fingers 35 and a portion of the arms 34 extend from the mouth 17. Then one of the arm portions 51 carrying the conductor 52 and a contact point 53 is slipped between the fingers 35 and the abutment 18 as shown in Figure 3 in dotted lines. Releasing the head 27 will cause the spring 36 to urge the U-shaped member towards the end 20 and the fingers will force the arm portions 51 against the relatively wide abutment 18 holding it in place with the point 53 projecting outwardly between the extremities of the fingers 35. If the arm portion 51 is quite broad, the arms may be spread to accommodate it, the particular shape of the mouth 17 permitting this, as is apparent from Figures 3 and 8. The novel tool may now be positioned so that the end of the point 53 may be brought against a suitable abrasive surface for grinding,—such as disposing the tool B in the groove 12, as well shown in Figure 1 and then sliding the tool forwardly to contact the point 53 with the wheel 10. Types similar to C are rather difficult to handle due to the double contacts, one at either end, but the novel device disclosed holds such types very firmly. It is obvious that upon urging the head 27 towards the end 16, the member C may be released.

Now, when it is desired to grind contact points on screws such as illustrated by D, the screw may be inserted into the bore 29, head 55 first and the set screw 32 be employed to position it so that the point 57 will project a sufficient distance from the end 20 and member 28. The plunger 23 is also retracted a sufficient distance to permit this and when the set screw 32 is sufficiently tightened, the plunger may be released so that the abutment 25 will rest upon the end of the head 55. The tool may now be placed in the groove 12 for grinding the point 57. Releasing the set screw 32 will cause the plunger to urge the screw contact D outwardly so that it may be grasped and removed.

When grinding a point such as that on the screw contact E, the plunger 23 may be retracted until the screw contact E may be dropped thru the aperture 21 as shown in Figure 5. If necessary the fingers of the hand may be employed to cause the shank 61 to enter the bore 29 and then upon releasing the plunger 23, the abutment 25 will contact the head 60 and force it against the abutment 30 of the member 28 so positioning the contact screw E as shown in Figure 6 in a proper position for grinding as heretofore described. Upon again retracting the plunger 23 and turning the tool so that the end 20 extends upwardly, the contact screw E will slide into the temporary compartment defined by the walls of the housing and the abutments 25 and 30 and by slightly revolving the tool, the contact screw E will drop out into the hand.

The type of contact shown at F is handled quite similarly to the double contact arm C by the fingers 35 and abutment 18 as is apparent in Figure 7.

5 From the above, it will be seen that a very useful hand tool is provided for the uses mentioned and one which will not be apt to become clogged by material ground off, may be manufactured at a relatively low cost, and may be 10 manipulated easily yet will firmly hold various types of contact arms or levers for grinding the points thereof.

Various changes may be made in the form of invention herein shown and described, without 15 departing from the spirit of the invention or the scope of the claims.

What is claimed is:

1. In a work holder, an elongated housing, a plunger slidable longitudinally within said housing, work holding means fixedly held at one end of said housing, work holding means slidably carried at the other end of said housing, and resilient means both normally urging said plunger towards said first named end to force 25 said plunger against the work held by said first work holding means and at the same time normally urging said second work holding means towards the end of said housing occupied by said first named work holding means.

2. In a work holder, an elongated housing, a plunger slidable within said housing, work holding means fixedly held at one end of said housing, work holding means slidably carried at the other end of said housing including a finger movable to overhang said last named end and extend towards the longitudinal axis of said body portion, and resilient means both normally urging said plunger towards said first named end to force said plunger against the work held by said first named work holding means and at the same time normally urging said second work holding means towards the end of said housing occupied by said first named work holding means and said finger into various planes paralleling the 45 transverse axis of said body portion.

3. In a work holder, an elongated housing, one end thereof being open and defining an abutment, a plunger slidable within said housing, work holding means fixedly held at the other end of said housing, work holding means slidably carried at the open end of said housing including a finger movable to extend into and out of said housing and disposed to extend substantially parallel with the face of said abutment, and resilient means both normally urging said plunger towards said second named end to force said plunger against work held by said first named work holding means and at the same time normally urging said second named work holding means towards the end of 55 said housing occupied by said first named work holding means, and said finger into various planes paralleling said face of said abutment, whereby work may be held between said finger and said abutment.

4. In a work holder, an elongated housing, a plunger slidable therein, work holding means fixedly held at an end of said housing, work holding means slidably carried at the other end of said housing including a pair of resilient arms extending from the inner end of said plunger and terminating at their free ends in a pair of spaced apart fingers disposed to extend inwardly towards the longitudinal axis of said housing and resilient means both normally urging said plunger towards 70 said first named end to force said plunger against

the work held by said first named work holding means and at the same time normally urging said arms and fingers towards the end of said housing occupied by said first named work holding means.

5. In a work holder, a tubular housing having an open end forming an abutment and also having a second end, a plunger slidably thru said housing and having a slot at its inner end, work holding means fixedly held at said second named end of said housing, work holding means slidably carried at the open end of said housing including a substantially U-shaped member, the bight portion thereof accommodated within said slot, and the arms thereof being resilient and slidable along the inner face of said tubular member, each of the free ends of said arms terminating in a finger extending inwardly towards the longitudinal axis of said tubular housing and substantially paralleling said abutment, and resilient means both normally urging said plunger against the work held by said first named work holding means and at the same time normally urging said second named work holding means towards the end of said housing occupied by said first named work holding means, including an expansible coil spring, having one end secured to said housing, and a pin extending thru an end of said coil spring and into said plunger and at said slot, said pin bridging said slot at a point between the ends of said plunger and said bight portion.

6. In a work holder, an elongated housing, a plunger slidable within said housing, work holding means rigidly held at one end of said housing, said means including a member having a central bore extending longitudinally of said housing and also having an abutment spaced inwardly of the end of said housing occupied by said member, work holding means slidably carried at the other end of said housing, and resilient means normally urging said plunger towards said member to force said plunger against the work held by said first named work holding means and at the same time normally urging said second work holding means toward the end of said housing occupied by said member.

7. In a work holder, a tubular housing, a plunger slidable in said housing, work holding means at one end of said housing, said means including a member having a central bore extending longitudinally of said housing, work holding means slidably carried at the other end of said housing, resilient means both normally urging said plunger towards said member and to force said plunger against the work within said first named work holding means and at the same time normally urging said second work holding means towards the end of said housing occupied by said first named work holding means, and means to selectively prevent longitudinal movement of said member and the work while in said bore.

8. In a work holder for holding ignition points, a tubular housing having an open mouth at one end, said mouth being restricted in width and of a length greater than the interior diameter of said tubular housing, a plunger slidable within said housing, work holding means carried at the end of said housing opposite said open mouth and work holding means slidably carried at the open end of said housing and including a pair of resilient arms extending longitudinally of said housing and lying within said restricted portion and each terminating in a finger extending across said mouth with the free ends of the fingers spaced from each other, and an expansion coil spring operatively connected to said plunger and arms to both nor-

5 mally urge said plunger toward said first named means to force said plunger against the work held by said first named means and at the same time to normally urge the arms and fingers of said second work holding means into said mouth, said spring being so mounted in said tubular housing that it is free to be contracted.

9. In combination with a grinding machine having an abrasive device and a base provided 10 with an elongated depression in the upper surface thereof with one end opening towards said abrasive device and the longitudinally extending plane

of said depression normally intersecting said abrasive device, an ignition point holder including an elongated tubular body portion adapted to be accommodated within said depression and provided with an ignition point gripping means largely within an end thereof and within the longitudinal planes of the walls of said depression, whereby said holder may be moved freely along said depression and towards said abrasive device to contact an ignition point therewith.
